Fig. 9

A technical diagram of a mechanical assembly. It features a central circular component labeled '42' with a smaller circle inside labeled '43'. Surrounding this are several numbered parts: '39' at the top, '40' on the left, '41' on the lower left, '44' on the right, '45' at the bottom right, '46' at the bottom center, and '46' at the bottom right. There are also two '14' labels, one on the top left and one on the top right. The assembly is mounted on a rectangular base with a central slot and two circular holes on the left side. A small '2' is written in the bottom right corner of the diagram.

UNITED STATES PATENT OFFICE.

AUSTIN CARL FISHER, OF ROCHESTER, NEW YORK, ASSIGNOR TO EASTMAN KODAK COMPANY, OF ROCHESTER, NEW YORK, A CORPORATION OF NEW YORK.

FOLDING CAMERA.

1,308,985.

Specification of Letters Patent.

Patented July 8, 1919.

Application filed March 12, 1917. Serial No. 154,179.

To all whom it may concern:

Be it known that I, AUSTIN CARL FISHER, of Rochester, in the county of Monroe and State of New York, have invented certain new and useful Improvements in Folding Cameras; and I do hereby declare the following to be a full, clear, and exact description of the same, reference being had to the accompanying drawings, forming a part 5 of this specification, and to the reference numerals marked thereon.

My present invention relates to photography and is particularly though not exclusively applicable to cameras of the folding type in which is employed an arrangement for automatically projecting the front and lens to approximately its operative position when the camera is unfolded. The improvements are directed toward providing such a front when so projected with means for accurately focusing it, such means being so designed and arranged as to be best adapted to the peculiarities of the projecting mechanism. To these and other ends the invention resides in certain improvements and combinations of parts all as will be hereinafter more fully described, the novel features being pointed out in the claims at the end of the specification.

30 In the drawings:

Figure 1 is a side elevation of a folding camera constructed in accordance with and illustrating one embodiment of my invention, the same being shown extended or in operative position;

Fig. 2 is a similar view illustrative of the manner in which the camera is folded;

Fig. 3 is a front view;

Fig. 4 is a section through the camera 40 when folded taken near the plane of the inner face of one of its side walls substantially on the line 4—4 of Fig. 3;

Fig. 5 is an enlarged detail fragmentary view in section on the line 5—5 of Fig. 3;

45 Fig. 6 is an enlarged detail fragmentary view in section on the line 6—6 of Fig. 3, showing the catch for holding the bed or door closed;

Fig. 7 is a horizontal section with the bellows removed, taken substantially on the line 7—7 of Fig. 1 and showing in plan the bed and lens carriage;

Fig. 8 is a detail fragmentary plan view of the front end of the bed and carriage

with the cover plate for the latter removed, 55 the view being partly in section and the carriage being in folding position;

Fig. 9 is a similar view showing the carriage advanced, as in focusing;

Fig. 10 is a detail section of the focusing 60 mechanism, being a fragmentary section taken substantially on the line 10—10 of Fig. 5, and

Fig. 11 is an enlarged detail fragmentary view of the rear of the carriage and front 65 taken in section transversely of the bed, substantially on the line 11—11 of Fig. 7.

Similar reference numerals throughout the several views indicate the same parts.

In the present embodiment, the camera 70 comprises a body 1 and a hinged bed 2 of the usual type that is supported when extended by links 3 and when closed, acts as a door or closure for the front of the body in which latter the front 4 and bellows 5 75 may be housed as shown in Fig. 4. A spring catch 6 having an upwardly turned locking lip 7 released by a button 8 projecting to the exterior of the body 1 holds the bed in folded position in a manner to be hereinafter described and when the catch is released, the bed is thrown to its extended or operative position and supported and locked there by the links 3 through the influence of a spring 9 surrounding the pintle 10 of the hinge 80 85 that connects the bed and body at 11.

In the practice of my invention, I provide at the forward end of the bed a carriage plate 12 (Fig. 8) that has a limited movement longitudinally thereof to project, 90 if desired, beyond its forward end, which carriage plate has slots 13 by means of which it is guided on headed pins 14 fixed in the bed. The sides of the carriage plate are turned upwardly into parallel flanges 95

15 while the front edge is formed into a hinge knuckle 16 coöperating with the knuckle 17 on a cross piece 18 connecting the arms or links 19 of an integral yoke that is thus pivoted on the pintle 20 to the forward end of the carriage. The links 19 work on the outer sides of the flanges 15 and at the forward ends of the latter are outwardly or laterally turned abutment ears 21. These act as stops defining the extended positions 100 of the links when brought forward under the influence of a spring 22 that surrounds the pintle 20.

The upper ends of the links 19 are pivoted at 23 to forwardly turned ears 24 on the sides of the front or lens board 4 and surrounding the pivots 23 are springs 25 bearing against studs 26 on the links and lens board, respectively, and tending to rotate the lens board so that its base will be urged forwardly. During such movement, the said base indicated at 27, passes between the flanges 15 until it abuts inwardly turned ears 28 thereon arranged near the rear ends of the flanges. When this engagement takes place, a vertically sliding catch or bolt 29 guided by means of pins 30 operating in a slot 31 in the front base 27 locks the latter to a rearward extension 32 of the carriage plate 12 by engaging in an aperture 33 in a depressed portion of said extension under the influence of a spring 34 (Fig. 11).

In the folded position of Fig. 4, the links 19 are folded rearwardly to a position against or substantially parallel with the bed 2 while the front 4 has been rotated forwardly on its pivotal connections 23 with the links to also lie parallel with and against the bed. As the button 8 is pressed and the bed 2 released, it swings forwardly to its open position immediately. At the same time, the links 19 swing forwardly under the influence of their spring 22 until stopped by the abutments 21 in the rearwardly inclined positions shown in Fig. 1 which raises the front 4. As soon as the latter is carried up sufficiently far, it begins to rotate upon the pivots 23 under the influence of its own springs 25 until its base 27 comes up against the abutments 28 and it is locked by the bolt 29. The front is then in an erect operative position on the carriage and it will be noted that inasmuch as it rests upon the rear end of the latter while the links 19 provide inclined braces at the front, a substantially triangular support for the lens of great rigidity is provided. To fold the camera, the bolt 29 is released by means of an operating portion 35 and the front 4 is grasped at the top and rotated forwardly and downwardly carrying the links 19 with it, as shown in Fig. 2. During this movement, the base 27 of the front, in swinging rearwardly on two centers, engages a rearwardly inclined tongue 36 on the bed 2 and is guided thereby to its proper folded parallel relationship with the bed in which position the tongue also supports it while the parts are folded, as clearly shown in Fig. 4. The bed is then closed against the body from the position of Fig. 2, as usual, whereat the parts remain confined in their folded positions as in Fig. 4.

The carriage plate 12 is, in the present instance, fitted with an overlying cover plate 37 held against it by two screws 38 but this is provided merely to give a finished appear-

ance and conceal the working parts of the carriage plate. It is in place in Fig. 7 and removed in Figs. 8 and 9, as previously mentioned.

During the operations heretofore described, the carriage plate 12 remains in its retracted position shown, for instance, in Figs. 7 and 8. After the front 4 has been extended to its operative position on the carriage, it may be necessary to move it forward or backward slightly to properly focus the lens. For this purpose, I secure to the bed 2 or, in the present instance, to a base plate 39 fastened thereon and that also carries the pins 14 and lateral flanges 40 for steadyng the carriage in its movements, a short rack 41 offset to one side. Geared to this rack is a disk or rotary member 42 pivoted at 43 on the under side of the carriage plate and projecting beyond the front edge of the latter at which point it is provided with an upwardly projecting operating handle 44. It will be seen that by moving this handle to the left (Fig. 10) the disk will move the carriage plate forwardly as shown in Fig. 9 while a reverse movement carries it back to the retracted position of Fig. 8, the said operating member being readily accessible and easily moved in a transverse direction across the front of the carriage plate.

Referring particularly to Figs. 5, 6 and 7, I also utilize this disk 42 as a means for locking the bed to the body as in Fig. 4. For this purpose, I form in the disk near its forward edge when in the position of Fig. 7, an opening 45 and the lip 7 on the catch 6 engages in this opening as the camera is closed in the manner best shown in Fig. 6. The fact that this opening does not have a fixed position is of no consequence as the camera cannot be closed anyway until the carriage 12 is retracted by rotating the disk to a position in which it will engage with the catch.

I am claiming herein only the features of the focusing device as the folding front is a separate invention, but both inventions are described herein as the focusing mechanism is particularly applicable to a folding front of this nature, as has been before mentioned.

I claim as my invention:

1. In a folding camera, the combination with a body and a hinged bed closing the front thereof, of a catch on the body, a front movable on the bed and a device movable relatively to the front to move it into focusing position and adapted to coöperate with the catch to hold the bed closed.

2. In a folding camera, the combination with a body and a hinged bed closing the front thereof, of a catch on the body, a front movable on the bed, and a rotary device for operating the front to focus it ar-

ranged on the bed forwardly of the front and adapted to coöperate with the catch to hold the bed closed.

3. In a folding camera, the combination with a body and a hinged bed closing the front thereof and provided with a rack, of a lens carriage movable on the bed and a rotary disk on the underside thereof geared

to the rack to move the carriage on the bed, said disk being provided with an upstanding operating portion arranged to swing across the front of the carriage. 10

AUSTIN CARL FISHER.
